ATTORNEY

UNITED STATES PATENT OFFICE.

ALEXANDER SELAS, OF PITTSBURGH, PENNSYLVANIA.

MICROMETER LOCK.

1,402,665.

Specification of Letters Patent. Patented Jan. 3, 1922.

Application filed August 28, 1920. Serial No. 406,604.

To all whom it may concern:

Be it known that I, ALEXANDER SELAS, a citizen of the United States, residing at Pittsburgh, in the county of Allegheny and State of Pennsylvania, have invented new and useful Improvements in Micrometer Locks, of which the following is a specification.

This invention relates to locking devices, and more particularly to means for locking a micrometer in adjustment.

One of the main objects of the invention is to provide simple and efficient means whereby the cylinder or stem of the measuring screw of a micrometer may be readily locked against rotation for preserving a measurement taken. A further object is to provide a locking device consisting of a minimum of parts and of very simple and efficient construction which may be readily applied to a micrometer of standard type. Further objects will appear from the detailed description.

In the drawings:-

Figure 1 is a side view of a micrometer of standard construction with a locking device constructed in accordance with my invention applied.

Figure 2 is a section taken substantially on line 2—2 of Figure 1.

Figure 3 is a detail of the locking member.

A micrometer 1, which is of standard construction, is provided at the inner end of bow 2 with a slot 3 which extends across and

is disposed at right angles to stem or cylinder 4 of the usual measuring screw operated in the well known manner. A cam member 5 is inserted in slot 3 and is supported by stem or cylinder 4, this cam member being provided with an extension forming a finger piece 6. By exerting pressure upon piece 6 this cam member may be forced tightly against the inner or upper wall of slot 3 so as to exert great pressure upon stem 4. This establishes a friction lock by means of which rotation of stem 4, and consequently the adjusting screw, is prevented thus locking the stem in adjustment and preventing accidental turning thereof. The lock consists of but a single piece which may be readily applied to a micrometer of standard type and, for this reason, may be applied at very small cost and without necessitating any material change in the construction of the micrometer itself.

What I claim is:-

In combination with a low micrometer including a rotatable measuring screw stem, the bow of the micrometer being provided with a slot extending across and disposed at right angles to said stem, a cam member pivoted on the screw stem and operating in said slot, said cam member being adapted by turning to contact with the inner end of the slot so as to exert pressure upon the screw stem for locking the same against rotation.

In testimony whereof I affix my signature.

ALEXANDER SELAS.
